CAR UNDERFRAME STRUCTURE

William O. Ashe, St. Louis, Mo., assignor to General Steel Castings Corporation, Granite City, Ill., a corporation of Delaware

Application December 15, 1933, Serial No. 702,447

4 Claims. (Cl. 105—415)

This invention relates to railway rolling stock and consists particularly in a novel underframe construction for freight cars with side doors, and more particularly automobile box cars.

Such car underframes heretofore have been provided with side sills of suitable section uniform throughout their lengths and frequently of channels with the flanges extending inwardly. In order to support the car flooring, which usually extends into the doorway to meet the side door, a separate member is mounted outside the portion of the side sill immediately beneath the doorway, which member may be an angle bar or a short length of timber. Also a reinforcing angle is frequently secured to the adjacent portion of the sill.

The main object of the present invention is to simplify and strengthen the construction of box car underframes and particularly the side sill portions thereof adjacent the side door openings. This object is attained substantially by forming each side sill of a continuous metal beam, the portion thereof beneath the doorway being of Z-section with the top flange extending outwardly into the doorway, this portion of the sill being deeper than the remaining portions thereof which may be conveniently of channel section with both flanges extending inwardly.

In the accompanying drawings which illustrate the invention—

Figure 1 is a top view of a box car underframe illustrating the invention.

Figure 2 is a side view of the same assembled with other portions of the car body.

Figures 3 and 4 are vertical transverse sections taken on the corresponding section lines of Figure 1 and showing flooring applied to the underframe.

Figure 5 is a detailed top view of a portion of the underframe and flooring adjacent a doorway.

The figures illustrate a box car integral cast under frame including side sills generally indicated at 1, center sill 2, bolsters 3, end sills 4, and transoms 5 and 5a. It will be understood that the general construction of the underframe as shown is not essential and the various structural members mentioned may be separately formed and assembled with each other in a built-up underframe. Secured to the side sills 1 are the superstructure side walls 6 reinforced by struts 7 and side door posts 8. The doorway openings 9 on opposite sides of the car are preferably

staggered in order to facilitate loading of automobiles into the car.

The portion of each side sill between the door posts 8 and forming the bottom member of the doorway framing is of Z-section, as shown in Figure 4, the web portion 10 thereof being substantially deeper than the web portions 11 of the remainder of the sill which are of channel section as in Figure 3. The top flange 12 of the Z-shaped portion of the sill extends outwardly while the flanges 13 of the channel shaped portions extend inwardly, diagonal gussets 14 being provided adjacent the door posts between the laterally offset portions of the sill top flanges. The top flange 12 of the Z-shaped portion of the side sill extends slightly inwardly of the web 10 and the top and bottom flanges 12 and 15 of this portion are approximately equal in width. Flanges 13 of the channel section parts of the sill are also of equal width.

The floor boards 16 are mounted upon the top flanges of the underframe longitudinal and transverse members 1, 2, 3, 4, 5 and 5a, which flanges are disposed in the same horizontal plane for this purpose. The flooring between the door posts 8 extends outwardly beyond the side walls of the car and the edge thereof is flush with the inner surface of the sliding door 17 supported by means of suitable bearings upon the track 18 disposed outwardly of the outer surfaces of the door posts.

The doorway extensions of the flooring are thus adequately supported by the side sill itself which is especially shaped for this purpose and additional members for supporting the floor extensions and for reinforcing the side sill are unnecessary. Obviously, the shaping of the portions of the side sill on each side of the doorway may be varied as desired and also the sill may be separately formed of one or more parts disposed lengthwise which may be secured together to form essentially a continuous side sill member in which the various parts are disposed to attain the maximum strength to fulfill the different functions thereof at different points with the use of a minimum amount of metal. The strength of the sill may be increased, as will be readily understood, by widening of the flanges and/or deepening of the upright web. The use of all such modifications as come within the scope of the appended claims is contemplated.

I claim:

1. In a railway car underframe side sill integral structure, a part with an inwardly extending top flange, an adjacent part forming a door-

way bottom frame and with an outwardly extending top flange offset laterally from the top flange of said first-mentioned part, and a diagonal connection between said top flanges, said 5 top flanges and said connection forming a continuous member of substantial width throughout for mounting flooring.

2. A railway car side sill member formed in part of channel-section, with both flanges extending solely inwardly, and in part of Z-section 10 with all but a small portion of the top flange thereof extending outwardly for supporting car flooring extending laterally beyond said channel-section part, said top flange and the upper of 15 said channel flanges being continuous with each other.

3. A railway car structurally complete side sill member formed of an upright web with top and bottom flanges, a part of said sill serving for

mounting door posts and wall structure, said flanges throughout said part extending solely in one direction from said web, at least the major portion of said top flange at another part of the sill extending in the opposite direction from said 5 web and forming a doorway bottom member, said top flange having a smooth upper surface for supporting car flooring and being horizontally continuous and of substantial width throughout whereby said top flange assists substantially in 10 resisting bending forces applied to the sill member.

4. A railway car underframe side sill having a channel-section part and a Z-section part and having laterally projecting flanges of substantial 15 width and extending continuously from end to end of the sill, said channel- and Z-section parts forming a structurally complete side sill.

WILLIAM O. ASHE.
